UNITED STATES PATENT OFFICE.

WALTER H. STROM, OF OAK PARK, ILLINOIS.

ANNUAL BALL-BEARING.

1,288,269.

Specification of Letters Patent. Patented Dec. 17, 1918.

Application filed August 15, 1916. Serial No. 114,966.

To all whom it may concern:

Be it known that I, WALTER H. STROM, a citizen of the United States, residing at Oak Park, in the county of Cook and State of Illinois, have invented a new and useful Improvement in Annular Ball-Bearings, of which the following is a specification.

My invention relates to certain new and useful improvements in roller bearings, 10 more particularly to a double-row annular ball-bearing capable of carrying satisfactorily both radial and axial loads. It is the object of the invention to provide a bearing of this type which may be easily assembled, 15 and in which in the assembly of the parts they are fitted to one another with a minimum amount of labor, and when completely assembled form a unitary structure.

The invention will be more fully understood from the following detailed description of one embodiment thereof taken in connection with the accompanying drawings, 20 in which—

Figure 1 is a side elevation of a double-row bearing constructed in accordance with the invention; Fig. 2 is a section through the center of the bearing in its own plane; Fig. 3 is an enlarged broken section taken on an axial plane as indicated by the line 3—3 25 of Fig. 1; Fig. 4 is a similar section illustrating the manner of assembly of the bearing; Fig. 5 is a similar section showing the last step of the assembling process, and Fig. 6 is a detail view of the retainer.

Referring more particularly to the drawings, the numeral 10 designates the inner race-member which is of the common annular form and is provided in its external surface with a wide and relatively shallow 30 race-way groove 11, the curved margins 12 of which constitute the actual race-way surface. For coöperating with this single inner race-member there is provided a pair of conjugate outer race-members designated 13 and 14, each in the form of an annulus or ring provided with a curved inner face designated 15, which, in the assembled position of the parts, as indicated in Figs. 3 to 5, faces an inner race-way 12. The outer 35 race-member 14 is counterbored as shown at 16, the counterbore extending inwardly a proper distance to permit the introduction of a ball as will later appear. The opposed

faces of the outer race-members 13, 14, are each provided with an oblique surface designated 17, and each of the race-ways is furthermore rabbeted out at its outer corner as illustrated at 18. The bearing balls, designated 19 and 20 for the balls in the two rows respectively, are secured in proper spaced relation by one or more retainers, such as the retainers 21 of which two are illustrated in the drawing, one being operatively related to each row of balls. As will later appear the retainer construction is not 55 pertinent to the present invention save in one particular.

To assemble the parts heretofore described, the row of balls 19 will first be placed in position upon the inner race-member 10. This may be done either before or after the balls 19 are secured in their retainer but it should be noted that if the balls are assembled in the retainer before being introduced into the race-way, it is 60 necessary that the retainer be of such construction as to permit the balls to move radially outward in their pockets a distance equal to the depth of the race-way or groove 11. Since the retainer for the balls 20 must 65 necessarily be of this construction as will later appear, I prefer to construct the two retainers in the same way for the sake of uniformity. The row of balls 19 and the retainer 21 having been assembled upon the 70 inner race-member 10 in the position shown in Fig. 4, the outer race-member 13 is then moved into position from the right-hand end of the bearing as viewed in Fig. 4. The outer race-member 14 may now be placed in 75 position, being slipped over the right-hand end of the bearing and moved axially until it abuts against the race-member 13 as shown in Fig. 4. The right-hand row of balls 20 having been previously assembled 80 in the retainer 21 is now slipped over the right-hand end of the inner race-member 10. In such movement each of the balls 20 will be forced outwardly in its pocket in the retainer as indicated by the dotted circles 20¹ 85 in Figs. 4 and 6, the counterbore 16 of the race-member 14 being sufficiently deep and of sufficient diameter to permit the balls to occupy the successive positions shown in dotted lines in Fig. 4.

To complete the assembly of the bearing

the outer race-members 13, 14, are moved away from one another and a split locking ring 22 of appropriate wedge-shaped cross-section is snapped into place in the groove 5 formed by the opposed oblique faces 17 of the two outer race-members. A retaining sleeve 23 formed of a malleable or ductile metal is now slipped over the outer cylindrical surfaces of the race-members 13 and 14, the bearing is placed in a chuck and a spinning tool pressed against the central portion of the sleeve 23 to crowd the metal of the latter radially inwardly into contact with the ring 22, which it should be noted is 10 of such size that its outer surface will lie below the cylindrical surfaces of the outer race-members. In this spinning operation by which the metal of the sleeve 23 is crowded inwardly to contract the ring 22 15 and force apart the outer race-members the proper adjustment of the bearing is simultaneously effected. Such pressure will be exerted and the spinning will be continued for so long as is required to take up all lost 20 motion and bring the parts to the proper working fit. In the spinning operation there will, in general, be formed a groove in the center of the sleeve 23, as is indicated at 25 24 in Fig. 5 of the drawings.

30 In order that the outer surface of the bearing may be truly cylindrical, and primarily also to prevent any subsequent loosening of the parts by reason of the ring 22 expanding and forcing the metal of the 35 sleeve back toward its original form, it is desirable to machine the outer surface of the sleeve 23 until the latter is truly cylindrical as is shown in Fig. 3. Either before or after this last machining operation, the outer 40 edges of the sleeve may be spun down into the rabbeted corners 18 so that the finished bearing presents the appearance shown in Figs. 1, 2 and 3.

As is quite clear from an inspection of 45 the bearing, it is capable of carrying radial loads as well as thrusts from either direction, and while in its construction three separate race-members are employed the finished bearing is a unitary device, all parts 50 of which are locked in operative position.

While I have shown and described in considerable detail one specific bearing construction embodying my invention together with the preferred method of assembling the 55 same, it is to be understood that this showing and description is illustrative only and for the purpose of making clear the nature and objects of my invention and that I do not regard the invention as limited to these 60 details nor to any of them except in so far as such limitations are included within the terms of the following claims, in which it is my intention to claim all novelty inherent in my invention as broadly as is permissible 65 in view of the prior art.

What I claim as new and desire to secure by Letters Patent is:

1. A double-row annular bearing comprising an inner race-member having in its outer surface opposed inwardly facing race-way surfaces, a pair of outer race-members, each having a race-way surface facing outwardly and opposed to one of the race-way surfaces of the inner race-member, two rows of roller bearings each row coöperating with one pair of the race-way surfaces and wedge-shaped means for locking the outer race-members in spaced relationship, whereby there is formed a unitary double-row bearing. 70

2. A double-row annular bearing comprising an inner race-member having opposed inwardly facing race-way surfaces formed on its outer face, a pair of outer race-members each of which has an outwardly facing race-way surface arranged in operative relation with one of the surfaces of the inner race-member, a row of roller bearings coöperating with each pair of race-way surfaces and a wedge-shaped locking member lying between the opposed end faces of the outer race-members and holding the latter in spaced relationship. 80

3. A double-row annular bearing comprising an inner race-member having opposed inwardly facing race-way surfaces formed on its outer face, a pair of outer race-members each of which has an outwardly facing race-way surface arranged in operative relation with one of the surfaces of the inner race-member, a row of roller bearings coöperating with each pair of race-way surfaces and an annular locking ring having a portion of wedge-shaped cross-section entering between the opposed end faces of the outer race-members and holding the latter in 90 spaced relationship. 95

4. A double-row annular bearing comprising an inner race-member having continuous uninterrupted race-way surfaces formed in its outer face and inwardly directed to oppose one another, a pair of outer race-members each having a continuous uninterrupted race-way surface opposing and in operative relation to one of the surfaces of the inner member, a row of spaced balls 100 coöperating with each pair of race-way surfaces, a retainer member for one of said rows of balls formed to permit of limited outward radial movement of the individual balls, and wedge-shaped means for locking 110 said outer race-members in spaced relationship. 115

5. A double-row annular bearing comprising an inner race-member having opposed inwardly facing race-way surfaces 125 formed in its outer face, a pair of outer race-members each having a race-way surface opposed to one of the inner race-way surfaces, a row of bearing balls arranged between each pair of race-way surfaces, 130

- and an endless ring surrounding said outer race-members and having the material thereof extending inwardly between the opposed end faces of the outer race-members 5 to hold the latter in spaced relationship.
6. A double-row annular bearing comprising an inner race-member having opposed inwardly facing race-way surfaces formed in its outer face, a pair of outer race-members each having a race-way surface opposed to one of the inner race-way surfaces, a row of bearing balls arranged between each pair of race-way surfaces, and an endless ring surrounding the outer race-members and extending inwardly between the opposed end faces thereof to hold the said members in spaced relationship, the outer surface of said ring being a true cylindrical surface.
7. A double-row annular bearing comprising an inner race-member having opposed inwardly facing race-way surfaces formed on its outer face, a pair of outer race-members each of which has an outwardly facing race-way surface arranged in operative relation with one of the surfaces of the inner race-member, a row of roller bearings coöperating with each pair of race-way surfaces, a locking member lying between the opposed end faces of the outer race-members to hold the same in spaced relationship, and an endless retaining ring surrounding the said outer race-members and engaging the said locking member.
8. A double-row annular bearing comprising an inner race-member having opposed inwardly facing race-way surfaces formed on its outer face, a pair of outer race-members each of which has an outwardly facing race-way surface arranged in operative relation with one of the surfaces of the inner race-member, a row of roller bearings coöperating with each pair of race-way surfaces, a locking ring of wedge-shaped cross-section lying between the opposed end faces of said outer race-members and an endless retaining ring having the metal thereof pressed inwardly to engage the outer face of said locking ring.
9. A double-row annular bearing comprising an inner race-member having opposed inwardly facing race-way surfaces formed on its outer face, a pair of outer race-members each of which has an outwardly facing race-way surface arranged in operative relation with one of the surfaces of the inner race-member, a row of roller bearings coöperating with each pair of race-way surfaces, a split locking ring of wedge-shaped cross-section lying between the opposed end faces of said outer race-members and when in assembled position below the outer cylindrical surfaces thereof, and an endless retaining ring sleeved over the outer surfaces of the said outer race-members and
- having the material thereof pressed inwardly to engage the outer surface of said locking ring.
10. A double-row annular bearing comprising an inner race-member having opposed inwardly facing race-way surfaces formed on its outer face, a pair of outer race-members each of which has an outwardly facing race-way surface arranged in operative relation with one of the surfaces of the inner race-member, a row of roller bearings coöperating with each pair of race-way surfaces, a split locking ring of wedge-shaped cross-section lying between the opposed end faces of said outer race-members and when in assembled position below the outer cylindrical surfaces thereof, and an endless retaining ring sleeved over the outer surfaces of the said outer race-members and having the material thereof pressed inwardly to engage the outer surface of said locking ring, the outer surface of said retaining ring being truly cylindrical.
11. A double-row annular bearing comprising an inner race-member having opposed inwardly facing race-way surfaces formed on its outer face, a pair of outer race-members each of which has an outwardly facing race-way surface arranged in operative relation with one of the surfaces of the inner race-member, means for holding said outer race-members in spaced relation, a row of roller bearings coöperating with each pair of race-way surfaces, and a locking member in the form of an endless ring sleeved upon the outer surfaces of said outer race-members and holding the same in spaced relationship, the edges of said ring being pressed inwardly to embrace the outer end faces of the outer race-members.
12. An annular double-row bearing comprising an inner race-member having opposed inwardly facing race-member surfaces formed in its outer face, a pair of outer race-members each having a race-way surface opposed to one of said inner race-way surfaces, a row of bearing balls lying between each pair of race-way surfaces, one of said outer race-members being counterbored in its outer end face, and means for holding said outer race-members in spaced relationship.
13. A bearing comprising concentric bearing members provided with opposed tracks forming race-ways, one of said bearing members consisting of two opposed parts movable axially with respect to each other to open up one of the race-ways, said parts having inclined opposing faces, a spacing member engaged between said inclined faces to wedge the parts of said two-part member away from each other and rolling elements in the race-ways aforesaid.
14. A bearing comprising concentric bearing members provided with opposed tracks forming race-ways, one of said bearing mem-

- bers consisting of two opposed parts movable axially with respect to each other to open up one of the race-ways, and one of said parts having an inclined face opposed to an abutment face on the other part, a spacing member engaged between said inclined face and abutment face to hold the two parts wedged apart and rolling elements in the race-ways aforesaid.
- 10 15. A bearing comprising concentric bearing members provided with opposed tracks forming race-ways, one of said bearing members consisting of two opposed parts movable axially with respect to each other to open up one of the race-ways, and said parts having opposed abutment faces, a spacing member
- having inclined faces engaging the abutment faces to wedge the parts of the two-part member apart and rolling elements in the race-ways aforesaid. 20
16. A bearing comprising concentric bearing members provided with opposed tracks forming race-ways, one of said bearing members consisting of two opposed parts movable axially with respect to each other to open up one of the race-ways, said parts having inclined opposing faces, a spacing member having inclined faces engaged between the inclined faces of the two-part member to wedge said parts away from each other and 25 30 rolling elements in the race-ways aforesaid.

WALTER H. STROM.
